Primary Examiner — Paula Greene(74) *Attorney, Agent, or Firm* — DeLio & Peterson, LLC(57) **CLAIM**

The ornamental design for a “door handle,” as shown and described.

DESCRIPTION

FIG. 1 is a perspective view of a “door handle” showing my new design in an unlocked position;

FIG. 2 is a perspective view showing my new design in a locked position;

FIG. 3 is a front elevational view showing my new design in the unlocked position of FIG. 1;

FIG. 4 is a right side elevational view showing my new design in the unlocked position of FIG. 1.

FIG. 5 is a left side elevational view showing my new design in the unlocked position of FIG. 1.

FIG. 6 is a top elevational view showing my new design in the unlocked position of FIG. 1; and,

FIG. 7 is a bottom elevational view showing my new design in the unlocked position of FIG. 1.

A back elevational view has not been provided as the back is mounted against the door and forms no part of my new ornamental design.

The broken lines form no part of the claimed design.
